UNITED STATES PATENT OFFICE.

JUDSON A. DE CEW, OF MONTREAL, QUEBEC, CANADA.

BED-PLATE AND SEGMENT FOR BEATING-ENGINES AND THE LIKE.

1,287,905.

Specification of Letters Patent.

Patented Dec. 17, 1918.

Application filed August 11, 1916. Serial No. 114,475.

To all whom it may concern:

Be it known that I, JUDSON A. DE CEW, a subject of the King of Great Britain, and resident of the city of Montreal, in the 5 Province of Quebec and Dominion of Canada, have invented certain new and useful Improvements in Bed-Plates and Segments for Beating-Engines and the like, of which the following is a full, clear, and exact description.

10 This invention relates to an improved material to be used for the segments and bed plates of pulp beating engines and similar machinery.

15 At the present time, the materials most generally used are basalt lava or metallic knives. The knives have a cutting rather than a rubbing or brushing out action necessary to separate the fibers of the material, 20 and are therefore of limited usefulness. The basalt lava is used on account of its hard and open or bubbly texture, which provides a multitude of pockets having edges over which the fragments of raw material are 25 dragged or brushed, with the result that the fibers are separated. The great disadvantage of this material is the difficulty of obtaining it in suitable grades. Sometimes the stone is too hard and fine grained and 30 sometimes so soft that it wears or crumbles away very rapidly. Furthermore, it sometimes happens that the pockets become filled with very closely compacted pulp material, so that the edges are covered and the brushing 35 or rubbing action is lost. The obvious results of any of the faults mentioned are a poor grade of pulp and in the case of the last mentioned, the necessity of dressing the stone segments and bed plate, to remove the 40 accumulations of compacted pulp and present fresh edges at the working surface. This operation means a considerable loss of time and a rapid wasting of the stone segments.

45 The material forming the subject of this invention is designed to be of a non-clogging nature, so that it may be continuously used, and is also designed to have a rough or gritty texture, so that the brushing or rubbing action necessary to separate the fibers

will be brought to a high degree of efficiency. The material consists briefly of a body of cementitious or other material, in which are embedded a multitude of small metal wires extending perpendicularly to the working 55 surface.

In the drawing which illustrates the invention:—

The figure is a sectional view of a fragment of the improved material taken perpendicular to the working surface.

Referring more particularly to the drawing, 11 designates a body or binder of cementitious or other suitable material or composition, which will be sufficiently hard and 60 gritty or rough textured to produce the desired brushing action. Bedded in the material and preferably extending the whole thickness thereof are a multitude of small metal wires 12 which extend perpendicularly to the working surface. The relative hardness of the body 11 and wires 12 is such that the body will wear more rapidly than the wires, so that the working surface of the material is mechanically roughened by 65 the projection of the ends of the wires. This projection of the wires forms in effect pockets or tortuous passages on the surface, through which the pulp material passes. The projection of the wires also protects 70 the body material 11 against undue wear. The body material 11 may be composed of Portland cement alone or mixed with a small amount of fine grained sharp sand, carbide, or even fine metal particles. 75 Water repellent material may be added. While Portland cement has alone been specifically referred to, it will be understood that the invention is not limited to this, as other cementitious material may be used, also materials of a non-cementitious character, such as materials formed by heating or vulcanizing processes, or even metals or alloys. If the binding material becomes worn down too far 80 below the ends of the wires to insure the proper brushing or rubbing effect, the segments may be very quickly and easily dressed by grinding off a small amount of the projecting wire ends, but with proper 85 selection of materials, it is not expected that 90

95 100

this will be necessary except at rare intervals, so that the material may be considered as continuously efficient.

Having thus described my invention, what

5 I claim is:—

A material for use in the segments and bed plates of pulp beating engines comprising a body of binding material of gritty or abrasive character having a rubbing or 10 brushing effect on fibrous material, and a

multitude of metal wires harder than the binding body in substantially parallel relation and extending to the working surface to present their ends at the working surface.

In witness whereof I have hereunto set my hand in the presence of two witnesses.

JUDSON A. DE CEW.
